[57] CLAIM

The ornamental design for a filter bag, substantially as shown and described.

DESCRIPTION

FIG. 1 is a perspective view of a filter bag showing my new design, the broken lines are for illustrative purposes only and form no part of the claimed design;

FIG. 2 is a right side elevation view thereof;

FIG. 3 is a front elevation view thereof;

FIG. 4 is a rear elevation view thereof;

FIG. 5 is a top plan view thereof;

FIG. 6 is a bottom plan view thereof; and

FIG. 7 is a left side elevation view thereof.

The crossline shading which is partially shown is understood to represent conventional fabric and to repeat uniformly across the body of the filter bag.
